(57) **CLAIM**

The ornamental design for a hitch ball protector, as shown and described.

DESCRIPTION

FIG. 1 is a top perspective view of a hitch ball protector in an environment of use, showing my new design;

FIG. 2 is a front elevation view thereof;

FIG. 3 is a rear elevation view thereof;

FIG. 4 is a top plan view thereof;

FIG. 5 is a bottom view thereof;

FIG. 6 is a left side elevation view thereof;

FIG. 7 is a right-side elevation view thereof;

FIG. 8 is a top perspective view thereof; and,

FIG. 9 is a front perspective view thereof.

The broken lines depict portions of the hitch ball protector that form no part of the claimed design.
